Inventor,

Samuel C. Bettiker,

By
A. D. Lawrence, Attorney.

UNITED STATES PATENT OFFICE.

SAMUEL CLAUDE BETTIKER, OF WARREN, OHIO.

MOISTURE-PROOF MAT.

1,356,593.

Specification of Letters Patent. Patented Oct. 26, 1920.

Application filed February 17, 1919. Serial No. 277,558.

To all whom it may concern:

Be it known that I, SAMUEL CLAUDE BETTIKER, a citizen of the United States of America, residing at Warren, in the county 5 of Trumbull and State of Ohio, have invented certain new and useful Improvements in Moisture-Proof Mats, of which the following is a specification.

My invention relates to improvements in 10 a moisture-proof mat or protector adapted primarily for use in working upon automobiles. The object of my invention is to produce a simple, cheap and compact article of this character, which is relatively water- 15 proof, light and durable.

The usual practice in the garage at the present time, is to provide a low wheeled platform or support, which is adapted to be moved from beneath one automobile to another, whereon the workman may rest or lie as he works beneath the machine. This device, however, is somewhat cumbersome, large and heavy, and rather imperfectly answers the general requirements in this respect. 25

My invention has proceeded with the idea of fully meeting the needs, not only of the garage, but of the automobilist while *en route*. The article of my invention comprises one or more sections of fibrous, cellular material, such as ordinary corrugated board; such sections preferably being suitably waterproofed, peripherally protected, and foldably united, as will be explained 30 35 more in detail in connection with the accompanying drawings, wherein:

Figure 1 is an isometric view of a mat embodying my invention.

Fig. 2 is an end view thereof, showing it 40 in folded relation.

Fig. 3 is an enlarged and exaggerated view of the corrugated structure preferably employed.

And Fig. 4 is a similar view illustrating 45 a modification wherein a plurality of thicknesses of corrugated material are used.

Throughout the several figures of the drawing I have employed the same characters of reference to indicate similar parts or 50 elements.

The mat of my invention preferably is constructed of two or more sections foldably united, but obviously the number of such

sections and their relation is wholly optional. The material used preferably is 55 fibrous and cellular, and preferably is waterproofed or moisture-proof, as I have termed it, but I do not wish to be understood as using these terms, except relatively, since absolute waterproofing is not at all necessary. 60

As also indicated, my improved mat preferably is constructed of corrugated board, but this material is not essential to the invention herein disclosed, nor is the mode of waterproofing the same. This latter pref- 65 erably is accomplished, however, by applying one or more coats of a suitable varnish, such as asphaltum varnish or the like. Suitable paint may also be used.

Referring to the drawing, the particular 70 mat illustrated is seen to comprise three sections, *a*, *b*, *c*, of suitable fibrous material or corrugated board; the latter adopted because of its lightness, strength and non-conducting properties. This is shown in the 75 drawing as a heavy composite board having a corrugated paper filler between two plane outer faces, known to the trade as double-faced corrugated board. Both surfaces preferably are made moisture-proof or 80 waterproof. Each section is provided with an attached border, *a'*, *b'*, *c'*, of suitable fabric, which serves to finish the article and protect it. Each section is attached to the adjacent section by a double canvas hinge; 85 the fabric border and hinges being readily secured by marine glue. The hinges are indicated in the drawing by the reference character *d*, but the sections may be suitably secured together by any adaptable hinge-member. The completed article may desirably be treated to one or more coats of a suitable varnish, or instead of using varnish, a suitable waterproofing paint may be applied, either by the brush or by dipping the 90 article or the individual sections, or by spraying them. As thus constructed, my improved device is extremely practical, in that it is provided with an exterior coating 95 as a whole, which is resistant both to dirt and moisture, while the waterproofed plane surfaces are separated by the cellular structure, also protected along the edges against moisture, and the hinge members even, afford like protection against dampness. 100 105 These features are of marked advantage in a

device which must be used alike upon a cold, oily garage floor, usually constructed of cement, or upon a wet road or pavement.

My improved mat or pad is light, compact and durable. It may be moved from place to place in the garage, and is very readily slipped into position beneath the automobile. When folded, moreover, it takes but little space and may be put beneath the seat or cushion of the car, where it will be available for instant use.

The modified structure of Fig. 4 affords a more resilient body for the mat and it is stiffer than the mat constructed of a single thickness of corrugated board. A plurality of thicknesses of fibrous or corrugated material, suitably cemented together and water-proofed, as already described, may accordingly be used for embodying my invention, when desired.

Having now described the preferred em-

bodiment of my invention, I claim as new and desire to secure by Letters Patent the following:—

A sectional folding mat, comprising adjacent sections of double-faced corrugated board positioned edgewise to each other and coated with a moisture-proof material throughout their top and bottom faces, fabric hinge members joining the aligned edges and cemented to said sections, and a peripheral fabric binding cemented about the outer edges of the united sections; said fabric members being water-proofed to complete a mat exteriorly impervious to dampness. 25 30 35

In testimony whereof I do now affix my signature in the presence of two witnesses.

SAMUEL CLAUDE BETTIKER.
